Attorney

UNITED STATES PATENT OFFICE.

JAN BÜCHTER, OF BERLIN, GERMANY, ASSIGNOR TO POWERS ACCOUNTING MACHINE CORPORATION, OF NEW YORK, N. Y., A CORPORATION OF DELAWARE.

CARD-PUNCH MECHANISM.

Application filed December 14, 1925. Serial No. 75,383.

To all whom it may concern:

Be it known that I, JAN BÜCHTER, a subject of the Kingdom of the Netherlands, and a resident of the city of Berlin, Germany, have invented certain new and useful Improvements in Card-Punch Mechanism, of which the following is a specification.

The present invention relates to a device for perforating statistical cards and more particularly to a punching means for identifying a card with a particular part such, for example, as the number designating a railroad car.

Some of the objects of the present invention are to provide an improved punching mechanism for statistical cards; to provide means by which errors due to reading off numbers of parts or cars are eliminated; to provide means for accurately and positively taking the identifying number of a part or car; to provide a punching mechanism whereby manual copying of identification numbers of railroad cars and the subsequent punching thereof is done away with; to provide a punching device attached to each part or car and having a set up identifying the part or car to which it is attached; and to provide other improvements as will hereinafter appear.

In the accompanying drawings Fig. 1 represents a front elevation of a punching apparatus embodying one form of the present invention, the cover for the same being removed; Fig. 2 represents a section on line 2—2 of Fig. 1; Fig. 3 represents a section on line 3—3 of Fig. 2; and Fig. 4 represents a portion of a card showing the field for identifying the subject of the card by number.

Referring to the drawings, one form of the present invention consists of a base 10 which is arranged to be mounted by any suitable fastening device to a fixed part with which it is used. The base 10 supports a punch plate or die 11 having registration perforations 12 and punch pin perforations 13, these last corresponding in arrangement to the predetermined number which is to be punched in the card 14.

In order to properly bring the card 14 into registered relation with the punch plate 11, a registration plate 15 is also supported by the base 10 and arranged parallel to but

spaced from the punch plate 11 in order to provide a card receiving passage 16, and it will be noted one end of this passage is open, as shown at 17, so that a card 14 can be inserted. The required registering of the cards is accomplished by registration perforations 18 in the card which are similarly arranged and of like number for all of the cards, so that when a card is properly located in the passage 16 the registration perforations 18 will be in register with the registration perforations 12 of the die 11 and like perforations 20 in the registration plate 15. The card 14 may then be held in such position by dowel pins 21 carried by the movable holder 22 which supports the punches 23 for perforating the card when the holder is moved towards the die 11. The punches 23 correspond in row arrangement with the number and row arrangement of the digits in the field of the card and are held rigidly clamped by a presser plate 24 held in place by fastening devices 25 engaging the holder 22.

For actuating the punches 23, the presser plate 24 and holder 22 are slidably mounted on guide pins 26 which are threaded into the base 10 and have springs 27 respectively encircling the pins and compressed between the pin heads 28 and the presser plate 24 to act as yielding buffers for the punch parts. The presser plate 24 is provided with spaced ears 30 for connecting an operating lever 31 thereto by means of a pin 32. The lever 31 is pivoted at 33 to the base 10 and has a handle 34 by which it can be manually operated. The lever 31, where it extends across the end of the punch mechanism, is provided with a rubber strip or yieldable buffer 35 which is arranged to engage a similar buffer 36 mounted on the base 10, when the punch is operated, for the purpose of gripping the card and closing the interior of the apparatus. A strip of rubber 37 or other yielding material is looped from a wall of the cover casing 38 of the apparatus to the strip 35 and can follow the movement of the lever 31 and maintain the interior of the casing entirely closed.

In the use of the punch of the present invention it is set up with a die 11 perforated in an arrangement corresponding to the

number which is to be punched in the card, while the movable punch mechanism is set up with punches to aline or register with the die perforations.

- 5 6 When a card is placed in the passage 16 its identification field has its digits properly registered respectively with the die 11 so that when the lever 33 is operated the punches will perforate the card in the required arrangement. As here shown the number of the car or part to which the punch is attached is taken as #21,372, and therefore the third punch in the first row is set up; the second punch in the second row; the fourth punch in the third row; the eighth punch in the fourth row; and the third punch in the fifth row. Thus if the device is used in a transportation system each car will be equipped with a punch set up with a number designating the car to which it is attached. When a car is ready to leave a station, a card is placed in the punch and perforated with the number of the car so that it then becomes an identifying card for that 25 particular car and all data thereafter punched in that card will relate to that particular car.

30 It will now be apparent that a complete unitary card punching mechanism has been devised for identifying railroad cars or other mechanisms with a number punched in a card, and wherein mistakes heretofore common in the punching of cards is eliminated in so far as the identifying means is concerned.

Having thus described my invention, I claim:

1. Identification means for movable carrier, comprising a casing to be attached to a carrier, a card receiving die therein and accessible only by cards inserted through an opening in a wall of the casing, a manually operable punch within said casing for perforating a card in said die, and an operating handle on said punch extending through a wall of the casing, said wall being formed to permit free movement of the handle without exposing the interior of the casing save for the card receiving opening. 40 45 50

2. A punching device comprising a base to be permanently attached to a car, a cover casing over said base and open at one end only, a card receiving die carried by said base within the casing and accessible only by cards inserted through the open end of the casing, a punch in said casing and pivoted at one end therein for perforating a card in said die, an operating handle on said punch and extending through the open end of the casing, said casing being formed at the open end to permit free movement of said operating handle, and a flexible closure at the open end of the casing between said punch and a wall of the casing 55 60 65 whereby the interior of the casing is closed save for the card receiving opening.

Signed at Berlin, Germany this 25th day of November, 1925.

JAN BÜCHTER.
